UNITED STATES PATENT OFFICE

JOSEPH S. BENNETT, OF MERION, PENNSYLVANIA, ASSIGNOR TO AMERICAN ENGINEERING COMPANY, OF PHILADELPHIA, PENNSYLVANIA, A CORPORATION OF PENNSYLVANIA

FLUID-COOLED WALL FOR DOUBLE-FIRED FURNACES

Application filed May 15, 1931. Serial No. 537,692.

This invention relates to improvements in tubular fluid-cooled walls of the type adapted for use in furnaces, retorts and the like for protection against excessively high temperatures and for the purpose of reducing clinker and slag adhesions.

In my copending application, Ser. No. 219,706, I have described a tubular fluid-cooled wall construction primarily adapted to installations of underfeed stokers of the type involving an inclined combustion grate. My present invention has to do with the application of this type of fluid-cooled wall to multiple-fired furnaces of the type including oppositely arranged stokers terminating in a common ash pit, and a principal object of the invention, therefore, is to provide in a multiple-fired furnace of the stated character a fluid-cooled wall having the desirable characteristics and advantages of the wall disclosed in my aforesaid copending application.

The invention further resides in certain novel and advantageous structural features and arrangements hereinafter described and illustrated in the attached drawings, in which

Figure 1 is a diagrammatic sectional view of a double-fired furnace equipped with a fluid-cooled wall made in accordance with my invention;

Fig. 2 is a diagrammatic sectional view of the fluid-cooled wall on the line 2—2, Fig. 1;

Figs. 3 and 4 are, respectively, fragmentary horizontal sectional view and front elevation illustrating a modification of my invention;

Figs. 5 and 6 are, respectively, fragmentary horizontal sectional and front elevational views illustrating a further modification;

Figs. 7 and 8 are, respectively, fragmentary horizontal sectional and front elevational views illustrating a still further modification within the scope of my invention;

Figs. 9 and 10 are, respectively, fragmentary horizontal sectional and front elevational views illustrating another embodiment of my invention;

Figs. 11 and 12 are, respectively, horizontal

sectional and front elevational views showing a modification within the scope of my invention in which the fluid-cooled wall structure is extended into the ash pit area of the furnace, and

Figs. 13 and 14 are, respectively, horizontal sectional and front elevational views illustrating still another modification within the scope of the invention.

With reference to the drawings, the numerals 1, 1 designate the inclined converging combustion grates of the oppositely arranged stokers of a double-fired furnace, said grates in a preferred form comprising alternately arranged tuyères and retorts and terminating at their lower ends in a common ash pit 2. Each of said grates is provided with the usual mechanism 3 located externally of the opposite walls 4, 4, of the furnace for feeding fuel to the upper ends of the various retorts and for operating the secondary fuel-feeding stoker elements (not shown) whereby the fuel is advanced at a predetermined rate downwardly over the grates, and the ashes and fuel refuse eventually deposited in the ash pit 2. In the present instance, the ash pit is shown as provided with crusher rolls 5 which operate in well known manner to discharge the ashes from the bottom of the pit.

In accordance with my invention, the opposite side walls 11 of the furnace are provided with fluid-cooled panels 12, 12, these panels in each instance bounding the side edges of the grates 1 and extending downwardly on converging lines substantially paralleling the inclination of the said grates. Preferably these panels 12, 12 are constructed in accordance with the principles set forth in my aforesaid copending application. In accordance with these principles, the walls 11 in a preferred embodiment are provided with inclined converging recesses corresponding in dimensions and position with the panels 12. Within each of these recesses is mounted a series of tubes 13 arranged in a flat bank extending longitudinally of the recess. The upper end of each of these banks of tubes is connected in the present instance to a header 14 located respectively in the walls 4, and at their lower ends the tubes of the respective

5 banks terminate, in the present instance, in a common header 15 which, as shown in Fig. 2, is cylindrical in form and which is set in the wall at the juncture of the said recesses. The headers 14 and 15 may be connected in an independent fluid-circulating system or to the water system of the boiler of which the furnace may constitute a part.

10 Attached to each of the tubes 13 of both banks is a series of blocks 16 which collectively form a protective facing for the said banks of tubes and which constitute the inner effective wall surface of the panels 12, 12, said blocks neatly filling the said recesses where-
15 by a continuous and preferably flush side wall is provided including the fluid-cooled panels 12 which, as illustrated, extend the full lengths of the grates 1, 1 in positions bounding the side edges of the latter.

20 While I prefer to construct this wall in accordance with the structural details set forth in my aforesaid copending application, it will be understood that there may be modification in the details of construction without departure from the invention in its broader aspects.

In Figs. 3 and 4 I have illustrated the lower converging ends of fluid-cooled panels of a wall construction similar to that described 30 above and illustrated in Figs. 1 and 2, with the exception that in the embodiment shown in Figs. 3 and 4, the tubes 23, 23, of the respective converging panels, instead of terminating in a common header, are extended 35 rearwardly beyond the junction point 24 and are respectively connected to headers 25, 25 set in the side wall 26 of the furnace. In this instance also, the tubes of the respective panels may be connected to entirely independent fluid-circulating systems, or may be individually connected to the boiler system of the furnace. Blocks 27 are employed to form a protective facing over the tubes 23, said blocks including a series 28 overlying the 40 junction of the lower ends of the tubes and forming with the adjacent surfaces of the wall 26 a continuous wall surface. In this instance also I have employed a suitable refractory cement 29 to seal the joints between 45 adjacent blocks.

50 Referring to Fig. 4, it will be noted that the blocks 28 of the series overlying the junction of the converging tubes 23 are rectangular in form, as also are the blocks of an adjacent vertical series, whereas the remaining blocks 27 are of parallelepiped form with their upper and lower edges inclined at an angle corresponding to the angle of inclination of the tubes 23. The arrangement affords ready means for covering the overlapping portions of the said tubes.

55 In the embodiment shown in Figs. 5 and 6, the converging tubes 33, 33 terminate at their lower ends in a common header 34 after the manner previously described and illus-

trated in Figs. 1 and 2. In this instance, however, the header 34 is offset rearwardly to an extent such that its forward face 35 lies substantially in the plane of the forward edges of the said tubes, the tubes where they join the said header also being offset rearwardly as illustrated. In this arrangement, I preferably provide protective blocks 36 to form the effective wall surface of the fluid-cooled panel, and certain of these blocks designated generally by the reference numeral 37 are so formed as to fit the junction area of the two sets of tubes and to overlie not only the lower ends of the tubes but also the forward face of the header 34.

60 In that embodiment of my invention shown in Figs. 7 and 8, the tubes 43 of the converging banks extend rearwardly at their lower ends to connect with a pair of headers 44, 44, at the back of the wall. The rearward extensions of the lower ends of the tubes 43 lie closely adjacent each other, and the space therebetween is filled with a suitable refractory cement 45, the forward face of this mass 45 forming with the blocks 46 a continuous wall surface and a protective facing for the tubes 43.

65 The embodiment illustrated in Figs. 9 and 10 is similar to that illustrated in Figs. 7 and 8, with the difference that in the embodiment of Figs. 9 and 10, the ducts 53 of the respective converging banks enter a single header 54 at their lower ends instead of the individual headers shown in the prior described embodiment. In this instance, the space at the forward side of the banks between the rearward extensions of the tubes is filled with a body of a suitable refractory cement 55, the usual protective blocks 56 being provided and forming with said cement 55 a continuous 70 fluid-cooled wall surface for the furnace.

75 In the embodiments shown in Figs. 7 to 10, inclusive, and also in Fig. 3, I have provided for expansion and contraction of the tubes due to temperature changes. The headers are placed well behind the tubes and the terminal ends of the latter connecting with the headers extend rearwardly from the plane of the wall at an angle permitting expansion and contraction of the tubes with substantial freedom from compressive and tensional strains. The refractory cement applied between the adjacent ends of the converging banks may be of such character as to permit the expansion of the tubes or may be so supported as to provide the necessary clearances.

80 In that form of my device shown in Figs. 11 and 12, the tubes 63 of the respective banks are extended downwardly in parallel arrangement so as to embrace within the cooled area the side wall of the furnace ash pit 2 at the lower ends of the grates. In this instance, the tubes of both banks join a horizontal header 64. The effective surface of the fluid-cooled panel in this instance is formed entire- 85

ly by the protective blocks 65, which are secured as a facing over the tubes 63 and which are carried down to the extreme lower ends of the tubes 63 where they join the header 64.

5 A further modification is illustrated in Figs. 13 and 14, in which the tubes 73 of the two banks connect at their lower ends to a pair of vertically arranged headers 74, 74. The forward sides of these headers are 10 exposed on the effective wall surface of the panel, and the space therebetween is filled by a mass of suitable refractory cement 75. Cement is also used to fill in the spaces between the refractory blocks 76 forming the 15 major portion of the protective facing and the spaces between the edges of the lower-most of these refractory blocks and the sides of the headers 74.

I claim:

20 1. A furnace comprising oppositely arranged inclined and downwardly converging combustion grates terminating in a common ash pit, and tubular cooling means for the side walls of the furnace comprising inclined and downwardly converging banks of tubes bounding the edges of said grates and extended at their lower ends to comprehend the sides of said ash pit within the cooled 25 areas, and headers for said tubes at the upper ends of the said grates and adjacent the bottom of the said ash pit.

2. A furnace comprising an inclined combustion grate terminating in an ash pit, and 30 a fluid-cooled panel bounding a side of said grate and comprising a plurality of tubes extending from the upper end of the grate to the bottom at an inclination corresponding substantially to that of the grate, said tubes at their lower ends being deflected 35 downwardly so as to embrace within the cooled area the side wall of said ash pit, and headers for said tubes located at the top of the combustion grate and adjacent the bottom of said pit.

40 3. A furnace comprising an inclined combustion grate terminating at its lower end in an ash pit, headers at the upper end of said grate and adjacent the bottom of the 45 ash pit respectively, and tubes connected with said headers and arranged to form a continuous fluid-cooled panel bounding the side of the combustion grate and embracing the side wall of said pit.

45 4. A furnace comprising an inclined combustion grate terminating in an ash pit, and a fluid-cooled panel bounding a side of said grate and comprising a plurality of tubes extending from the upper end of the grate 50 to the bottom at an inclination corresponding substantially to that of the grate, said tubes at their lower ends being deflected 55 downwardly so as to embrace within the cooled area the side wall of said ash pit, headers for said tubes located at the top of the 60

combustion grate and adjacent the bottom of said pit, and liner elements secured in contact with said tubes and forming a substantially continuous plane wall surface extending from the top of the combustion grate to 70 the bottom of said pit.

JOSEPH S. BENNETT.
